UNITED STATES PATENT OFFICE.

CURTIS M. SMITH, OF WASHINGTON, DISTRICT OF COLUMBIA, AND HERMAN WEIGAND, OF LA CROSSE, KANSAS.

REFRIGERATING APPARATUS.

1,383,246.

Specification of Letters Patent. Patented June 28, 1921.

Application filed January 16, 1919. Serial No. 271,465.

To all whom it may concern:

Be it known that we, CURTIS M. SMITH and HERMAN WEIGAND, citizens of the United States, and residents of Washington, 5 District of Columbia, and La Crosse, Kansas, respectively, have invented certain new and useful Improvements in Refrigerating Apparatus, of which the following is a specification.

10 Our invention is designed to provide a simple and economical absorbent system of refrigeration and to save the various expense in the initial cost and operation in the well known compressor systems and to economize in the known methods of absorption.

15 In the accompanying drawing,

Figure 1 is a diagrammatic view showing our invention as attached to a well known system of condenser coil receiver and ice 20 tank, while

Fig. 2 is a sectional detail of one of the absorbing units.

It has been heretofore proposed in an absorption system to use a substance such as 25 nitrate of ammonium in a rotating cylinder receiving the spent gas, which goes into solution with the nitrate but while such a system is very effective it requires the rotation of the cylinders in order to keep the absorption effective and the ammonium nitrate is 30 limited in its absorbing power while we have produced a device by reason of a different absorption material which requires no movement of the cylinders and which will absorb 35 a larger proportion of the ammonia gas the absorbent not going into solution.

In the drawing the condensing coil A, the receiver B and the ice tank C are of ordinary or usual construction and the low pressure 40 gas issues from the ice tank through the pipe a. A cylinder b is provided with a head c and a diaphragm d, the latter supporting a series of tubes e. The perforated tube f is held within each of the tubes e, 45 the perforations being formed by kerfs g and between the walls of the inner and outer tubes we place our absorbent material, which is preferably composed of anhydrous calcium chlorid mixed with charcoal of a 50 granular form having a grain about that of coarse ground coffee. The chlorid and charcoal are mixed dry and are filled in the space between the two tubes, as shown at h', and as the gas flows through the pipe a, i, h, 55 into the space k it passes the length of the

tubes f and gains access through the perforations and the end of the tube f to the absorbent material, where it is perfectly and uniformly absorbed. After absorption has taken place to the fullest extent possible the 60 valve l is closed, so that no more gas enters this unit and hot water or steam is let in through the valve m from the steam supply pipe n and this circulating in the cylinder around the tubes e will volatilize and drive 65 off the ammonia gas and this will pass out through the pipe h and o to the condenser and receiver and make the circuit as usual. We prefer to have two or more units so that while one is absorbing the other is generating.

While absorption is taking place the cylinder b is cooled by water from the pipe p and the branch pipes q. A drain pipe is shown at r. A pressure device is shown at s.

75 While we prefer to use a mixture of the anhydrous calcium chlorid and charcoal preferably charcoal made of peach stones in the proportion of about ten per cent. of the charcoal and ninety per cent. of the anhydrous calcium chlorid we do not limit ourselves in this particular as the anhydrous calcium chlorid may be used alone, though it is not as effective as used with the charcoal, as the latter material keeps the chlorid 80 from packing and makes it more absorbent, and while we might use the charcoal alone it is not as effective as an absorbent material as the anhydrous calcium chlorid and hence 85 we prefer to use the two materials in substantially the proportions indicated.

90 We are able by the use of our absorbent to carry out the process in a very simple apparatus and very effectively and economically.

95 We may also employ instead of the anhydrous calcium chlorid, another chemical of the deliquescent chlorid group, namely zinc chlorid, but we prefer the anhydrous calcium chlorid as we find this gives better 100 results.

The charcoal prevents the calcium chlorid from packing. When the calcium chlorid is heated it expands and it contracts when cool and unless some means is provided such as the charcoal, the calcium chlorid would pack into a mass and lessen the absorption capacity of a given quantity of the chlorid.

105 The charcoal serves to keep the calcium chlorid in a divided condition and provides 110

for the free access of the gas to all parts of the mass of the chlorid while holding it in this separated condition.

The calcium chlorid is held in a thin layer about the tubes so that there is not more than one-half inch thickness of calcium chlorid at any point, and this assures that the mass of calcium chlorid will be quickly affected by the heating and cooling agents.

10 The charcoal in addition to performing its function as a separating means for the calcium chlorid also serves as an absorbent and as means by which the gas is conveyed to the particles of the chlorid, so that there will be no isolated portions of the chlorid which the gas cannot reach. When the heat is applied it drives the gas off from the charcoal as well as from the chlorid.

What we claim is:

20 1. In an absorbent ice machine a receptacle containing a series of containers, each container holding an absorbent material in tubular form, thereby providing an open center for the easy access of the ammonia

gas to be absorbed, substantially as described.

2. In an absorbent ice machine a cylinder, a series of containers located therein, each container having an absorbent material with an open center, the length of the containers, so that the ammonia gas has ready access to the absorbent material and means for heating and cooling the said containers, substantially as described.

3. In an absorbent ice machine the combination of a chamber, containers located therein, each comprising an outer tube and an inner perforated tube, absorbent material filling the annular space between the outer and inner tubes, means for heating and cooling the chamber, and a conduit for the ammonia gas connecting with the interior of the perforated tube, substantially as described.

In testimony whereof, we affix our signatures.

CURTIS M. SMITH.
HERMAN WEIGAND.
